SAFETY OUTLET PLUG HAVING INSULATED ELECTRODES

Laurice D. Ely, Culver City, Calif.
(2862 Stromboli Road, Costa Mesa, Calif. 92626)

Filed Mar. 15, 1971, Ser. No. 124,656

Term of patent 14 years

Int. Cl. D13—03
U.S. Cl. D26—1 B

The FIG. 1 is a perspective view of a safety outlet plug having insulated electrodes showing my new design;

The FIG. 2 is an end elevational view thereof;

The FIG. 3 is a side elevational view thereof taken from either side of FIG. 2;

The FIG. 4 is a top elevational view thereof;

The FIG. 5 is a bottom plan view thereof;

The FIG. 6 is a side elevation view of a modified form thereof wherein the only difference resides in the side elevation appearance of the bellows element, as shown.

I claim:

The ornamental design for a safety outlet plug having insulated electrodes, as shown and described.
